UNITED STATES PATENT OFFICE.

WYNN MEREDITH, OF ALAMEDA, CALIFORNIA, ASSIGNOR TO PETROLEUM RECTIFYING COMPANY, OF SAN FRANCISCO, CALIFORNIA, A CORPORATION OF CALIFORNIA.

AUTOMATIC DISCHARGE MEANS FOR DEHYDRATORS.

Application filed October 28, 1920. Serial No. 420,246.

To all whom it may concern:

Be it known that I, WYNN MEREDITH, a citizen of the United States, and resident of the city and county of Alameda, State 5 of California, have invented new and useful Improvements in Automatic Discharge Means for Dehydrators, of which the following is a specification.

My invention has for its object means 10 for controlling the discharge from dehydrators whereby a desired level of oil in the dehydrator is retained at all times to prevent the trapping of gas or vapors from the treated emulsion in the container or 15 treatment chamber, which trapping of vapors has heretofore proved a fire menace due to the inflammability of the said vapors, especially in the presence of an electrical discharge. It is advisable to operate dehydrators of this type without 20 material internal pressure, maintaining merely upon them sufficient pressure to facilitate the circulation of the emulsion being treated, and due to the difference in specific 25 gravity of the emulsion during different periods of its treatment, and the desirability of withdrawing the treated oil from the treatment chamber, it has heretofore proven difficult to control the outflow so as to 30 prevent the trapping of the said vapors. My invention is particularly applicable to the closed type of electric dehydrator wherein the said dehydrator takes place within a closed chamber to prevent the 35 escape of the valuable hydrocarbon vapors. Other objects will be observed from the drawings and specifications which follow.

Referring to the drawings:

Fig. 1 illustrates, somewhat diagrammatically, a closed electric dehydrator employing my invention.

Fig. 2 is a plan view of Fig. 1.

Fig. 3 is an enlarged cross-section of my adjustable discharge device.

Throughout the figures similar numerals refer to identical parts.

The dehydration or treatment chamber is indicated by the numeral 1 having electrodes therein and suitable electrical connections and operating device in the compartment 2 formed on the top thereof of the chamber 1.

At 3 is a discharge pipe of relatively large dimensions connected to the chamber 55 1 near its lower part and rising to and pro-

vided with an outlet sleeve 4 of smaller diameter. The sleeve 4 is threaded on its exterior, preferably throughout its length, and is in threaded engagement with the reducer 5 so that by rotating the sleeve 4 60 its top, or discharge outlet 6, may raise or lower with respect to the dehydrating chamber 1. The threaded products from the dehydrator 1 may therefore be caused to flow through the outlet 6 by raising or 65 lowering the sleeve 4 to adjust its position of discharge with respect to the top 7 of the dehydrator 1 so that the pressure of the emulsion in the treatment chamber 1 will cause a discharge through the outlet 6. 70 This discharge occurs within the box 8, having a loose cover thereover at 9 and from the box 8 will be caused to flow by gravity through the outlet pipe at 10, after which the treated products are conveyed to settling tanks not shown but well known wherein the treated oil and water separate out by gravity. It will be observed that the column 3 and inlet 11 are of relatively 75 large diameter so that as the products from the hydrocarbon oils descends into the treatment chamber 1 they will undergo partial separation, there being a layer of water upon the bottom of the chamber 1, which will discharge to the exclusion of oil until 80 such time as the oil body in the chamber 1 above the said water layer will fall to the top of the outlet 11 at which time oil globules will flow into the pipe 3 and will rise there-through and discharge at the outlet 6 into the box 8. There will thus be maintained at all times a flow of all of the water down to the level of the outlet and any further outflow will be from the oil body raised upon the said water layer. It will 85 thus be seen with the discharge means of my invention there will be discharged the maximum water contents supplemented by treated oil and that these in their partially separated condition will flow freely from the outlets 6 in its adjusted position just sufficient to maintain the container filled with the emulsion to the level of its top 7 regardless of the variations in flow from the oil inlet pipe 12 or of the specific gravities of the emulsion during the treatment in the chamber 1, and this will occur without the trapping of any vapors in the treatment chamber or elsewhere.

Reference is herein made to my copend- 110

ing applications Serial Nos. 420,244 and 420,245, filed October 28, 1920.

I claim:

1. In combination with an emulsion dehydrating chamber, a pipe connection to the lower part of said chamber and rising therefrom, an outlet member adjustably connected to said pipe whereby the elevation of the discharge from said pipe and said member may be varied to maintain the chamber full and without substantial pressure therein.

2. Apparatus as set forth in claim 1 and a receptacle surrounding said outlet member adapted to catch the overflow of emulsion after treatment from said outlet member, and a duct to drain said treated emulsion from said receptacle.

3. Apparatus as set forth in claim 1 wherein the pipe and its port to said chamber are of relatively large cross section to

trap partially separated oil and water substantially as and for the purpose described.

4. Apparatus as set forth in claim 1 where-in the pipe and its port to the chamber are of relatively large cross section and a receptacle surrounding said outlet member adapted to catch the overflow from said outlet and drain means for said receptacle substantially as and for the purpose set forth.

5. Dehydration apparatus comprising a chamber and means therein for treating an emulsion, an outlet pipe from said chamber and disposed on the lower side thereof, said outlet pipe directed upward and provided with an adjustable outlet normally disposed slightly above the top of the chamber, a receptacle into which treated emulsion overflows from said pipe outlet and a duct for draining said receptacle as and for the purpose set forth.

WYNN MEREDITH.
